Primary Examiner — Brett Miller(74) *Attorney, Agent, or Firm* — Smith, Gambrell & Russell, LLP(57) **CLAIM**

The ornamental design for a combination grill and smoker, as shown and described.

DESCRIPTION

FIG. 1 is a front perspective view of a combination grill and smoker;

FIG. 2 is a front view thereof;

FIG. 3 is a back view thereof;

FIG. 4 is a left side view thereof;

FIG. 5 is a right side view thereof; and,

FIG. 6 is a top view thereof.

The broken lines immediately adjacent the shaded areas represent the bounds of the claimed design while all other broken lines are directed to environment and are for illustrative purposes only; the broken lines form no part of the claimed design.
